UNITED STATES PATENT OFFICE.

THOMAS L. GARDNER, OF AKRON, OHIO.

BALL-BEARING CASTER.

1,198,717.

Specification of Letters Patent. Patented Sept. 19, 1916.

Application filed October 28, 1915. Serial No. 58,464.

To all whom it may concern:

Be it known that I, THOMAS L. GARDNER, a citizen of the United States, residing at Akron, in the county of Summit and State of Ohio, have invented certain new and useful Improvements in Ball-Bearing Casters, of which the following is a specification.

This invention relates to improvements in furniture casters and like devices, and 10 has for one of its objects to improve the construction and increase the efficiency and utility of devices of this character.

Another object of the invention is to provide a simply constructed device embodying 15 a plurality of anti-friction balls which may be readily disposed within the supporting body of the caster and removed therefrom when required.

Another object of the invention is to provide a device of this character embracing a 20 plurality of relatively small anti-friction balls which are held in position within the body or supporting portion of the caster and will not fall therefrom when the larger 25 bearing ball is detached, while at the same time the smaller balls may be readily detached by applying a suitable implement thereto.

With these and other objects in view the 30 invention consists in certain novel features of construction as hereafter shown and described, and then specifically pointed out in the claim.

Referring to the drawings, Figure 1 is a 35 side elevation of the improved device; Fig. 2 is a bottom plan view of the parts shown in Fig. 1; Fig. 3 is an elevation with the lower portion in section on the line 3—3 of Fig. 1; Fig. 4 is a transverse section on the 40 line 4—4 of Fig. 3.

Corresponding and like parts are referred to in the following description and indicated in all the views of the drawings by the same reference characters.

The improved device comprises a body or 45 stock 10 having means such as a spindle 11 of the usual construction whereby the stock may be supported from a table leg, bedstead, or other article of furniture. The body portion 50 10 is preferably flared outwardly and downwardly and is formed with a flat lower face 12 and is reduced at the edge to form an externally threaded annular shoulder 13. Formed in the lower face of the body 10 is 55 a cavity, represented as a whole at 14, and with an annular runway or channel 15

somewhat larger than the intake end of the cavity and likewise extending above the bottom of the cavity whereby a downwardly projecting central portion 16 having a convex face is produced. The annular runway 15 is designed to receive a plurality of anti-friction balls 17, the balls being limited in their inward movement and supported in position by the downwardly projecting central portion 16 of the stock. By this arrangement it will be obvious that when a sufficient number of the balls 17 to completely fill the runway 15 are disposed within the cavity, as shown in Fig. 4, with 65 their adjacent faces in contact, the depressed central portion 16 will operate to retain the balls in place and prevent them from dropping downwardly, while at the same time the balls may be readily removed 70 by exerting a slight downward pulling movement thereon. It will be understood, however, that said balls can not be removed except force be applied to detach them. A relatively large bearing ball 18 is disposed 75 within the cavity 14 and in contact with the smaller anti-friction balls 17, as illustrated in Fig. 3. A holding member 19 having a central cavity 20 forms a part of the improved device, and is provided with a 80 threaded rim 21 to engage the threads 13 of the stock 10 and with a flat upper face 22 to engage against the flat lower face 12 of the stock, as shown in Fig. 3. The socket or cavity 20 of the member 19 underlaps the 85 bearing ball 18 to a sufficient extent to retain the latter in position when the weight is removed from the article of furniture to which the device is applied, to prevent the bearing ball from dropping out, while at the same time the member 19 will not engage the bearing ball when the caster is in use. 90

The stock 10 will preferably be made of metal and the interior cavity including the runway 15 may be turned on a suitable machine, and all the other portions turned true, at small expense, so that the improved device runs true and smooth. A suitable oil duct 23 is formed in the head 10, as 95 shown in Fig. 3, to enable the balls to be lubricated, if required.

Having thus described the invention, what is claimed as new is:—

A caster including a head having a socket 110 formed therein and provided with a projection depending from the head immediately above the socket and having a convex

lower face surrounded by an annular runway, portions of the walls of the runway being formed by the convex face of the projection and other portions thereof being inclined downwardly and intersecting the walls of the socket, there being an oil duct formed in the upper portion of the head and communicating with the annular runway near the convex lower face of the projection, a master ball seated in the socket,

a plurality of anti-friction balls seated in the runway and bearing against the master ball, and a retaining cap holding the master ball in contact with the anti-friction balls and serving to prevent accidental displacement of said anti-friction balls when the parts are assembled. 15

In testimony whereof, I affix my signature.

THOMAS L. GARDNER. [L.S.]
